FILLING AND DISPENSING SPOUT

George W. Cooke, Baldwin, N. Y., assignor to
Devco, Inc., New York, N. Y., a corporation of
New York

Application November 6, 1933, Serial No. 696,756

8 Claims. (Cl. 221—28)

This invention relates to certain new and useful improvements in filling and dispensing spouts and more particularly to dispensing receptacles of the non-refillable type. It is particularly adapted for use with a standard quart size bottle for containing a standard brand of oil or other liquid.

One object of this invention is to prevent the substitution of an inferior grade of oil for the standard brand purported to be dispensed from the glass bottle.

Another object of this invention is a gravity operated dispensing device which cannot be utilized for refilling except when brought into proper co-operative registry with a predetermined form of filling nozzle connected to the proper filling source.

Another object of this invention is a filling and dispensing spout employing one common orifice 20 for receiving and discharging the dispensed liquid. Other objects will appear from the detailed description.

In the drawings comprising two sheets of 10 figures numbered Figs. 1 to 10 inclusive one embodiment of the invention is illustrated.

Fig. 1 is a vertical central sectional view of the device.

Fig. 2 is a horizontal sectional view taken along the line 2—2 of Figure 1 looking in the direction of the arrows.

Fig. 3 is a vertical section of the device.

Fig. 4 is a detailed view of the locking connection between the spout and receptacle.

Fig. 5 is a horizontal sectional view taken along the line 5—5 of Figure 4 looking in the direction of the arrows.

Fig. 6 is an inverted sectional view of the device of Figure 3.

Fig. 7 is a perspective view of a portion of the 40 interior valve mechanism.

Fig. 8 is a vertical sectional view of the filling nozzle.

Fig. 9 is a horizontal section taken along the line 9—9 of Figure 8 looking in the direction of the arrows; and

Fig. 10 is a vertical sectional view of the spout and filling nozzle in co-operative registry.

The bottle 49, a portion whereof only is shown in Figs. 1, 3, 4 and 6, is a standard quart size bottle such as is commonly used in gasoline filling stations for containing a standard brand of oil. The standard quart size glass bottle is provided with a neck having a screw thread 50 molded therein. The frusto-conical spout 10 may have 55 the trade-mark and/or grade-mark or other

identifying characteristic (not shown) of the distributing company and/or its product cast, molded, or otherwise impressed, in the wall of the spout 10, to apprise the customer of the brand of the oil purchased.

The frusto-conical spout 10 is provided with a tubular extension 11 constituting an orifice for the free passage of the oil or other liquid to be dispensed. At its base spout 10 is provided with an outwardly extending lateral flange having a 10 downwardly extending collar 13 provided with an internal screw thread 14 for threaded engagement with the screw thread 50 of the bottle neck. The spout 10 is thus designed to be screwed into place upon the neck of any standard quart size 15 glass bottle. To prevent the spout from being removed from the bottle the bottom flange of collar 13 is drilled to receive a press-fitted steel ball 51 (or pin) which will obstruct the free passage of the screw thread 50 of the bottle in the 20 screw thread 14 of the cap when the spout 10 is rotated relative to the bottle 49 in a direction to unscrew the same.

Positioned within the frusto-conical spout 10 is a valve mechanism 24 consisting of an internally 25 and externally rabbeted seating ring 25 substantially Z shaped in cross-section. This seating ring is designed to rest upon the inwardly projecting seat formed by the junction between the laterally projecting flange and the downwardly 30 extending collar 13 of the spout 10. The channel formed in the underside of the seating ring 25 constitutes an annular guide-way for the gasket 8 which may be made of any suitable material such as leather, rubber or of metal as preferred. 35 The channel formed in the upper face of the seating ring 25 serves as a valve seat for the shutters 41—41 which are normally held seated against said valve seat under tension of the spring 47 (Figs. 1, 2 and 7). The seating ring 25 is reinforced with the web 26 whereon spring 47 is anchored as at 46. Seating ring 25 is also recessed as at 27—27 (Fig. 7) to accommodate the anchored ends 44—44 of the shutters 41—41. Certain of the anchoring ends 44—44 are each provided with an ear-like extension 45 for receiving the free ends of the spring 47.

Secured to the underside of web 26 is an inlet valve mechanism consisting of a cylindrical cup 28 having a plurality of apertures 29 therein defining ports and a bottom port 40. A valve stem 31 is connected with cylindrical cup 28 in any suitable manner as by a screw thread (Fig. 1), and communication between bore 31a of valve stem 31 and cylindrical cup 28 is normally pre- 55

vented by a metal ball 30 which is normally seated upon the end of valve stem 31 under tension of coiled spring 39. The upper end of valve stem 31 is provided with one or more ports 34, said ports being normally closed by the sleeve 33 which is slidably movable relative to valve stem 31 to open and close ports 34. Sleeve 33 normally closes ports 34 under the influence of coiled spring 35 pressing against flexible washer 38 which is retained in position by the collar 32. The limit of upward movement of sleeve 33 is determined by hook 36 which is secured to sleeve 33 by a rivet 37 and which engages the shoulder defined by the underside of collar 32 against the action of coiled spring 35.

The wall 12 of the spout 10 is heavily reinforced at 16, and said reinforcement being vertically drilled from above and below to provide parallel chambers which are then inter-connected by a plurality of horizontal passages 18 and 19. An elbow tube 22 is connected to the inner end of passage-way 19 and passes downward through a suitable opening in web 26 into the bottle 49. In this manner bottle 49 is vented to atmosphere under control of a gravity operated ball 21 which is normally seated so as to close the port between chamber 20 and passage-way 19. The outer end of chamber 20 is plugged as at 9 and direct communication between chamber 20 and atmosphere is cut off by the tubular member 23 which is press-fitted into chamber 17 so as to seal the mouths of passage-ways 18 and 19, the tip of tubular member 23 being bevelled to allow intercommunication between chamber 17 and passage-way 18, so that air can only be admitted to, or expelled from bottle 49 by way of elbow tube 22, port normally closed by gravity operated ball 21, chamber 20, passage-way 18, chamber 17 and tubular member 23 downward to atmosphere.

Thus it will be observed that no liquid can be admitted into bottle 49 except by way of bore 31a and ports 34. Any liquid poured through orifice 11 will encounter shutters 41—41 and the weight of the liquid will only tend to form a more secure seal between L shaped flanges 42 of the shutters 41 and their co-acting valve seats 48 (Fig. 3). Any attempt to force the liquid into the bottle 49 by way of elbow tube 22 will be prevented by the ball 21, and should the bottle be turned so as to unseat the ball 21, the entrance of the liquid into the bottle 49 would compress the air in the bottle thereby lifting the shutters 41 and causing some of the liquid to escape. The L shaped flanges upon shutters 41 are snugly fitted in the rabbeted channel of valve seat 48 to prevent lifting of the shutters 41 by the insertion of a hook like implement into the orifice 11.

The bottle is designed to be filled only when the spout 10 is brought into proper co-operative registry with a nozzle 58 (Fig. 8) connected with the genuine source of liquid supply. Nozzle 58 consists of a tubular member 60 having an inwardly projecting lateral flange 61 constituting a valve seat for a metal ball 62. The tubular member 60 is slightly smaller in diameter than the internal diameter of the orifice 11, while the opening in said tubular member normally closed by the ball 62, is slightly larger in diameter than the end of the valve stem 31 so that when the nozzle 58 is inserted in the orifice 11 in correct registry therewith the tubular member 60 engages sleeve 33 and slides the same downward to uncover the ports 34 thereby connecting bore 31a of valve stem 31 with the bore of tubular member 60. The collar of spout 10 is provided with a plu-

rality of projections 15 for engaging within a plurality of key-ways 63 (Fig. 8) adapted for co-operative registry therewith. Tubular member 60 is in turn slidably supported in a sleeve 55 forming an extension of a nipple 52. Sleeve 55 and tubular member 60 are keyed together by a spline 64 slidable in a guide-way 57 to retain said members in position to insure correct alignment of ports 65 and 54 (Fig. 8). Sleeve 55 is capped with a screw cap 69, and coiled spring 67 acts against an annular shoulder formed in tubular member 60 to normally prevent registry of the ports 65 and 54 and to seal the mouth of the latter against the wall of tubular member 60. Nipple 52 is internally threaded as at 53 to connect with a source of oil supply (not shown).

To refill an empty bottle, the operation is as follows: Orifice 11 of spout 10 is brought into co-operation with nozzle 58 with projections 15 of spout 10 and recesses 63 of the nozzle in co-operative registry. Bottle 49 is then forced upwards causing the end of sleeve 33 to engage the end of tubular member 60. By applying upward pressure to bottle 49 sleeve 33 is caused to slide relative to valve stem 31 against the tension of coiled spring 35 to uncover ports 34, while at the same time tubular member 60 slides relative to sleeve 55 against the increased tension of coiled spring 67 to bring ports 65 and 54 into registry. The outer end of valve stem 31 unseats metal ball 62 thereby establishing a passage-way between the bore 31a of the valve stem 31 and port 54 of nipple 52 by way of the bore of tubular member 60 and port 65. The oil or other liquid now flows from the source of supply by way of nipple 52, ports 54 and 65, bore of tubular member 60, ports 34 and bore 31a of valve stem 31 (see Fig. 10), and the pressure of the oil overcomes the tension of coiled spring 39 to unseat metal ball 30 and the oil now flows through the ports 29 and 40 into bottle 49 until the desired level is reached when the attendant releases bottle 49 whereupon the telescopic expansion of tubular member 60 in sleeve 55 immediately seals ports 54 and 65, to shut off any further flow of the oil from the source of supply. As soon as the pressure of the oil is removed, coiled spring 39 forces the metal ball 30 against the mouth of the valve stem 31 thereby retaining a column of oil in the valve stem.

As the oil flows into the bottle 49 the air is forced upwards into the tubular elbow 22 thereby lifting ball 21 from its seat to permit the escape of the air to atmosphere by way of chamber 20, passage-way 18 and tubular member 23. The bottle being now filled with oil to proper capacity, a suitable spring cap 70 (Fig. 1) may be snapped over the orifice 11 to exclude foreign matter.

When it is desired to dispense the contents of bottle 49 the orifice 11 of spout 10 is brought into registry with the mouth of the container to be filled at which time the spout will be downwardly inclined. The weight of the oil will now rest upon the shutters 41 which will open outwards (Fig. 6) against the pressure of spring 47 permitting the contents of the bottle to flow through the ports thus uncovered into the frusto-conical chamber of spout 10 thence by way of orifice 11 into the container to be filled. While the bottle is thus turned upside down ball 21 (Fig. 1) will fall under the influence of gravity against the plug 9 thereby connecting the bottle to atmosphere; ball valve 21 now functions as a compensating valve to permit air to enter and

replace the oil. The metal ball 30 will remain seated against the mouth of valve stem 31 under the tension of coiled spring 39, and the sleeve 33 will likewise continue to seal port 34 so that the column of oil contained in bore 31a of valve stem 31 will not be affected.

It should be observed that this improved filling and dispensing spout employs one common orifice for both filling and dispensing, and is designed for use with a standard quart size glass bottle having the regulation screw threaded neck so that this improved filling and dispensing spout can be used in conjunction with existing bottle equipment which is a great saving to the company whose product is to be dispensed because it eliminates the necessity of junking the existing equipment and of substituting hundreds of thousands of special containers therefor.

What is claimed is:

1. In a bottle top for dispensing receptacles and in combination, a spout having but a single opening therein for receiving a nozzle for admitting fluid into the receptacle and for discharging the fluid contents therefrom, and valve means positioned within the spout normally effective to prevent the admission of the fluid into the receptacle but operable responsive to the insertion of the nozzle in the spout opening in correct registry therewith to permit the filling of the receptacle.

2. In a bottle top for dispensing receptacles and in combination, a spout having but a single opening therein for admitting fluid to, and dispensing the contents of, the receptacle, valve mechanism positioned within the spout and normally effective to prevent refilling by pouring fluid into the spout opening, but operable in co-operative registry with a filling nozzle to permit filling of the receptacle, and other valve mechanism positioned within the spout and opened by the gravity flow of the fluid when the receptacle is placed in the dispensing position.

3. In a bottle top for dispensing receptacles and in combination, a spout having a common filling and discharge opening therein, valve mechanism carried within the spout to permit refilling the receptacle in co-operative registry with a filling nozzle but not otherwise, and other valve mechanism operable responsive to the gravity flow of the fluid when the receptacle is placed in dispensing position.

4. In a bottle top for dispensing receptacles and in combination, a spout having a common filling and discharge opening therein, and a plurality of normally closed valves carried within the spout to prevent refilling by pouring fluid into the common opening, one of said valves being operable in co-operative registry with a filling nozzle to permit filling of the receptacle, and another operable responsive to the gravity flow of

the fluid when the receptacle is placed in dispensing position.

5. In a bottle top for dispensing receptacles and in combination, a frusto-conical spout, the smaller end thereof constituting a common filling and discharge opening, and a plurality of valves carried within the spout and normally closed to prevent refilling by pouring fluid into the common opening, one of said valves being operable in co-operative registry with a filling nozzle to permit filling of the receptacle, and another operable responsive to the gravity flow of the fluid to permit its free passage in the direction of discharge, when the receptacle is placed in dispensing position.

6. In a bottle top for dispensing receptacles and in combination, a frusto-conical spout, the smaller end thereof constituting a common filling and discharge opening, and a valve carried within the spout and operable responsive to the gravity flow of the fluid to permit its free passage in the direction of discharge when the receptacle is placed in dispensing position, said valve having a rabbeted seat to guard against access to the valve for lifting it from its seat.

7. In a bottle top for dispensing receptacles and in combination, a spout having a common filling and discharge opening therein, inlet and outlet valve mechanism carried within the spout, said inlet valve mechanism being effective to prevent refilling of the receptacle by pouring fluid into the common opening but operable in co-operative registry with a filling nozzle to permit filling of the receptacle, said outlet valve mechanism being operable responsive to the gravity flow of the fluid when the receptacle is placed in the dispensing position, and a compensating valve for controlling the direction and flow of air into and out of the dispensing receptacle.

8. A bottle top for a screw topped dispensing receptacle, said bottle top having a compensating valve comprising two vertical openings extending part way through the wall of said bottle top one from above and the other from below, and horizontal upper and lower openings extending from the outer wall into said vertical openings, a ball valve seated in the vertical opening extending from above to control the passage between said opening and the lower horizontal opening, the mouth of the said vertical opening being sealed to retain said ball valve within the passage-way defined by said opening and to cut off free communication between said passage-way and atmosphere, and a bevel ended tube press-fitted into the vertical opening extending from below to seal both horizontal openings against free access to atmosphere, while permitting free communication between the vertical opening extending from below and the upper horizontal opening.

GEORGE W. COOKE.
